WILLIAM K. HOLMES, OF GREAT NECK, NEW YORK.

MAGAZINE PENCIL.

Application filed July 20, 1927. Serial No. 207,233.

This invention relates to magazine pencils of the type which are adapted to contain a supply of leads which are successively fed to a projected writing position without the necessity of taking the pencil apart.

The invention more specifically comprehends a reciprocatory lead-feeding mechanism which includes a novel clutch and clutch-actuating means which is positive in its action and which positively precludes breakage of the leads by the grip of the clutch.

The invention furthermore comprehends an improved reciprocatory lead-feeding mechanism which functions in connection with leads of standard diameter irrespective of their length.

As a still further object the invention comprehends in a magazine pencil a lead-feeding mechanism which is so constructed as to positively preclude jamming or clogging.

Other objects reside in the simplicity of construction of the pencil and the lead-feeding mechanism thereof, the economy with which the same may be produced, and the general efficiency derived therefrom.

With the above recited and other objects in view, reference is had to the following specification and accompanying drawings in which there is exhibited one example or embodiment of the invention, while the appended claims define the actual scope of the invention.

35 In the drawings—

Figure 1 is a side view of a magazine pencil constructed in accordance with the invention;

Fig. 2 is an enlarged longitudinal sectional view therethrough taken approximately on the line 2—2 of Fig. 1, and illustrating the lead-feeding mechanism in its normal retracted position;

Fig. 3 is a similar view illustrating the lead-feeding mechanism in its projected position;

Fig. 4 is a fragmentary longitudinal sectional view through the pencil with the lead-feeding mechanism in elevation and with the parts in the position illustrated in Fig. 1;

Fig. 5 is a similar view with the parts in the position illustrated in Fig. 3;

Fig. 6 is a similar sectional view with the lead-feeding mechanism in section and with the parts in the position illustrated in Fig. 4;

Fig. 7 is a similar view with the parts in the position illustrated in Fig. 5;

Fig. 8 is a cross-sectional view taken approximately on the line indicated at 8—8 in Fig. 4;

Fig. 9 is a similar sectional view taken approximately on the line indicated at 9—9 in Fig. 5;

Fig. 10 is a perspective view of the clutch element removed from the pencil.

Referring to the drawings by characters of reference, 11 designates an outer shell or casing which is of the conventional cylindrical form and which is provided with a tapered lower end 12. A lead tube 13 extends axially upward from the tapered end and is secured to the outer shell or casing at this point in any desired manner. Preferably the lead tube is attached to a substantially frusto-conical sleeve 14 which is soldered or otherwise secured within the tapered end 12 of the outer casing, a portion of the outer end of the lead tube projecting therebeyond, which portion is longitudinally slotted at 15 to provide a radially contractile lead-gripping means which prevents accidental or gravitational discharge of the lead from the lead tube. The lead tube has an internal diameter approximately the same as the diameter of the leads L which are used in connection with the pencil. Except for an intermediate portion said lead tube is formed with an enlarged bore 16 and at this point the tube is provided with diametrically opposite slots 17 of the same length as the enlarged bore 16 and is further provided with upwardly extending exterior grooves 18 in prolongation of the slots. At its extreme upper end the tube is provided with an enlarged annular head 19, the upper surface 20 of which tapers toward the central bore of the tube. A clutch element designated generally at 21 composed of a strip of resilient material bent medially of its length into substantially V-shape to provide a bight portion 22 and a pair of divergent arms 23 connected by the bight portion. The clutch element is cut away at 24 centrally from the bight to a point spaced from the free ends of the arms, the said cut-away portion being of a width approximately equal to the distance between the inner walls of the grooves 18. The uncut terminals or free ends 25 of the arms are of a length slightly less than the length of the slots 17, the difference determining the length of the

90

100

105

110

lead to be fed upon each operation of the feeding mechanism. The clutch element is inserted in the lead tube 13 with the uncut terminals or free ends 25 extending across 5 or intersecting the enlarged bore and with the remainder of the arms extending upwardly where they are received by and guided in the grooves 18. The uncut terminals or free ends 25 are provided with 10 longitudinal medial substantially semi-circular grooves 26 which are preferably produced by offsetting said portions outwardly. Under this arrangement it is obvious that the clutch mechanism 21 is associated with 15 the lead tube for upward and downward sliding relation limited by the engagement of the opposite ends of the uncut portions 25 with the opposite ends of the slots 17. The inherent normal tendency of the arms 20 is to separate as far as possible and in this condition the grooved portions 26 are sufficiently spaced apart to freely slide over the lead L which is disposed in the lead tube.

A clutch-actuating member 27 in the 25 nature of a slidable collar is mounted on the lead tube and said collar is slotted at diametrically opposite points downwardly from the upper end to provide continuous slots enlarged above as at 28 and reduced below as at 30 and connected by gradual convergences as at 30. The upper end of the collar 27 is provided with an enlarged head 31 defining at its juncture with the remaining portion of the collar, a shoulder 32. A coiled expansion 35 spring 33 is interposed between the shoulder 32 and the sleeve 14 for normally moving the collar 27 axially upward. The outer side edges of the arms 23 are adapted to be engaged respectively by the diametrically disposed slots 28 and 29 of the collar. The enlarged head 32 of the collar is provided with a central annular groove 34 and an inner tubular shell 35 is swivelly connected with the head 32 by an inwardly bent annular 40 bead 36. The opposite or upper end of the inner shell 35 projects through the upper end of the outer shell or casing 11 and has frictionally telescoped therethrough a hollow cap 37 the downward movement of which cap is limited by an outwardly turned annular bead 38. The upper end of the inner shell is further closed, if desired, by an eraser 39 which frictionally telescopes within the inner shell and is limited in its downward movement by an inwardly turned annular bead 40. The enlarged head 45 of the lead tube is of a size to approximately fit the internal diameter of the inner shell 35 and between the head 19 and the eraser 39, the inner shell serves as a magazine for the leads L.

In use and operation, the spring 33 normally moves the collar 27 axially upward with respect to the lead tube until the outer 50 most ends of the reduced slots 29 engage

with the side edges of the arms 23 at which point the arms are advanced toward each other to maintain the groove portions 26 in gripping relation to the lead in the lead tube. The operator grasps the outer casing or shell 70 11 in the four fingers of the hand and with the thumb presses downwardly on the cap 37 to move the inner shell 35 axially downward thereby moving the clutch actuating collar 27 downwardly. The initial movement 75 of the clutch collar 27 downwardly, carries the clutch and the lead L gripped thereby downwardly until the free ends of the uncut terminals 25 engage with the lower or outer ends of the slots 17 in the lead tube. This arrests further downward movement of the clutch and lead, while the clutch actuating collar 27 continues to move until its lower ends abuts the sleeve 14. This further movement of the clutch actuating collar 80 27 beyond the movement of the clutch 21, causes the enlarged inner slots 28 to register with the arms 23 of the clutch element and permits the inherent resiliency of the clutch 85 element to separate the arms for releasing the gripping action of the clutch on the lead, while the clutch is at rest. When the operator releases the pressure on the cap 37, the spring 33 functions to slide or move the clutch collar axially upward. The initial movement of the clutch collar upwardly 90 carries the clutch 21 therewith while the side edges of the arms 23 are in the enlarged inner slots 28. When the upper edges of the uncut terminals 25 engage with the upper ends of the slots 17, the clutch element comes to rest while the clutch actuating collar 27 continues to move upwardly to a point where the reduced outer slots 29 function to advance the terminals 25 of the clutch toward 95 each other to again grip the lead in the lead tube. This sets the clutch mechanism for a subsequent operation to feed the lead downwardly through the pencil tip, while locking the lead against upward movement when 100 the pencil is in use.

In operating the pencil it is always advisable to point the tapered end 12 downwardly in order that the leads L in the magazine will feed into the upper end of the lead tube by gravity. By swiveling the inner shell 105 to the clutch-actuating collar, damage to the pencil is prevented in event a user unfamiliar with the mode of use of the pencil should attempt to turn the cap. Any length leads may be used in the pencil but leads of sufficient length to extend completely through the lead tube are preferable for the reason that leads of longer lengths when 110 engaged with the clutch mechanism may be projected by the lead-feeding mechanism irrespective of the position in which the pencil is held. In magazine pencils it is never advisable to project too great a length 115 of lead through the tip of the pencil and 120

where too great a length has been projected, the same may be retracted by pressing the cap inwardly to release the clutch and pushing the lead upwardly while the clutch is so released.

What is claimed is:

1. In a magazine pencil, a lead tube, and a reciprocating lead-feeding mechanism including a clutch element having limited 10 slideable relation with the lead tube comprising a pair of substantially semi-circular spring separated jaws defining when in contact an opening having a diameter slightly less than the lead, said jaws each having 15 a pair of laterally projecting ears and a clutch actuating member having slotted portions cooperating with the ears whereby said member is slideable with and beyond the clutch in opposite directions for moving 20 the clutch therewith in one direction while gripping the lead and in the opposite direction while released from the lead.

2. In a magazine pencil, an outer shell having a tapered end, a lead tube secured 25 to and extending axially inward from the tapered end defining a bore of a diameter approximating the diameter of the lead and having its intermediate portion formed with a relatively enlarged bore and provided with 30 diametrically disposed slots intersecting said enlarged bore, said lead tube having diametrically disposed exterior grooves extending inwardly in prolongation of said slots, a substantially V-shaped resilient 35 clutch element having a bight and a pair of divergent arms, said clutch element being cut away centrally from the bight to a point adjacent the free ends of the arms, the uncut portions thereof being of a length 40 slightly less than the length of the slots and formed with substantially longitudinal semi-circular grooves of a diameter slightly less than the lead, a clutch actuating collar mounted on the lead tube for sliding move- 45 ment having diametrically arranged slots, each having an enlarged inner portion and a reduced outer portion receiving therein and coacting with the outer edges of the clutch arms, means normally moving the 50 collar inwardly to engage the reduced portions of the slot with the clutch arms, whereby to grip the lead to cause its outward movement with the clutch and collar, the clutch being arrested in its outward 55 movement by engagement of the free ends of the clutch arms with the outer ends of the lead tube slots, the collar being further movable in said direction until the enlarged inner end of the collar slots aline with the 60 free ends of the clutch to allow for opening of the same and to permit inward movement of the clutch while released, continued movement of the collar causing the reduced slotted portions of the collar to contract the

free ends of the clutch about the lead for 65 subsequent outward movement.

3. A magazine pencil including in combination, a stationary lead tube having an intermediate portion formed with an enlarged bore and provided with diametrical- 70 ly disposed slots intersecting said enlarged bore and a reciprocating lead feeding mechanism comprising a pair of outwardly spring pressed semi-circular clutch jaws dis- 75 posed within the enlarged bore and of lesser length than the slots, laterally projecting ears on the jaws extending through the slots and a reciprocating clutch actuating collar slideable on the lead tube having diametrical- 80 ly disposed slots, each of which has wide and narrow portions cooperating with the ears of the clutch jaws to respectively effect movement of the clutch jaws therewith for a portion of its stroke in one direction while said jaws are released, and a move- 85 ment of the jaws therewith for a portion of its stroke in the opposite direction while said jaws are gripping the lead.

4. In a magazine pencil, a stationary lead tube and a reciprocating lead feeding mech- 90 anism including a clutch element comprising a pair of semi-circular outwardly spring pressed gripping jaws defining when in contact with each other an opening having a diameter slightly less than that of the lead, 95 said jaws having laterally projecting ears and a clutch sliding member slideable on the lead tube and having communicating slotted portions of relatively different widths co- 100 operating with the ears of the clutch jaws to respectively effect the movement of the clutch with said member in opposite direc- 105 tions while gripping the lead and while released from the lead.

5. In a magazine pencil, a stationary lead tube and a reciprocating lead feeding mech- 110 anism including a clutch element comprising a pair of semi-circular outwardly spring pressed gripping jaws defining when in contact with each other an opening having a diameter slightly less than that of the lead, 115 said jaws having laterally projecting ears and a clutch sliding member slideable on the lead tube and having communicating slotted portions of relatively different widths 120 cooperating with the ears of the clutch jaws to respectively effect the movement of the clutch with said member in opposite directions while gripping the lead and while released from the lead, said member being movable beyond the clutch in one direction to cause release of the clutch while the same is at rest and movable beyond the clutch in the opposite direction to cause gripping of the lead by said clutch while 125 the same is at rest.

6. A magazine pencil including in combination, a stationary lead tube having an

- intermediate portion formed with an enlarged bore and provided with a slot intersecting said bore and a reciprocatory lead feeding mechanism comprising a circumferentially contractible normally expanded clutch disposed within the enlarged bore and of lesser length than the bore of the slot, means for circumferentially contracting the clutch extending laterally through the slot and a reciprocatory clutch actuating member slideable on the lead tube having means cooperating with the clutch contracting means to respectively effect movement of the clutch therewith for a portion of its stroke in one direction while said clutch is expanded and movement of the clutch therewith for a portion of its stroke in the opposite direction while the clutch is contracted and gripping the lead. 30
- 10 the slot and a reciprocatory clutch actuating member slideable on the lead tube having means cooperating with the clutch contracting means to respectively effect movement of the clutch therewith for a portion of its stroke in one direction while said clutch is expanded and movement of the clutch therewith for a portion of its stroke in the opposite direction while the clutch is contracted and gripping the lead, said member being 35 movable beyond the clutch in one direction to cause expansion and release of the same from the lead while the clutch is at rest and movable beyond the clutch in the opposite direction to cause contraction of the 40 clutch and gripping of the lead thereby while said clutch is at rest.
- 15 7. A magazine pencil including in combination, a stationary lead tube having an intermediate portion formed with an enlarged bore and provided with a slot intersecting said bore and a reciprocatory lead 45 feeding mechanism comprising a circumferentially contractible normally expanded

Signed at New York city, in the county of New York and State of New York, this 16th day of July A. D. 1927.
